United States Patent Office.

J. J. ANDREW, OF SALTILLOVILLE, INDIANA.

Letters Patent No. 87,232, dated February 23, 1869.

IMPROVEMENT IN STRAW-CUTTERS.

The Schedule referred to in these Letters Patent and making part of the same.

To all whom it may concern:

Be it known that I, J. J. ANDREW, of Saltilloville, in the county of Washington, and in the State of Indiana, have invented certain new and useful Improvements in Straw-Cutter; and do hereby declare that the following is a full, clear, and exact description thereof, reference being had to the accompanying drawings, and to the letters of reference marked thereon.

The nature of my invention consists in the shape and arrangement of the knife of a straw-cutting machine, as will hereinafter be more fully set forth.

In order to enable others skilled in the art to which my invention appertains, to make and use the same, I will now proceed to describe its construction and operation, referring to the annexed drawings, which form a part of this specification, and in which—

Figure 1 is an end view, and

Figure 2, a side view, in section.

A represents the usual box of a straw-cutter, the throat of which rests in or on a frame, B.

In the throat of the box A is a steel bar, C, placed flush with the edges of the box, so that the knife will work close against the same.

Above the throat of the box, and in the frame B, is a cross-bar, D, which extends beyond the frame on one side; and to this end a lever, E, is pivoted.

To the inner side of the lever E, across the throat of the box, is secured the knife F.

This knife is somewhat angular-shaped, one side being nearly perpendicular from the lever, and the

other side slanting from the lower point to the lever, the base of the knife, where secured to the lever, being about the same width as the box.

The slanting side of the knife is sharpened, so as to cut the straw easily.

The perpendicular side of the knife is, of course, nearest to the handle of the lever.

Around the throat of the box A, on the frame B, is a metal guard or guide, H, between which and the frame the knife operates.

By this arrangement, a straw-cutter may be made considerably cheaper than any now in use, and is fully as strong and durable.

Having thus fully described my invention,

What I claim as new, and desire to secure by Letters Patent, is—

1. The angular-shaped knife F, constructed and operating substantially as and for the purposes herein set forth.

2. The combination of the box A, frame B, steel bar C, cross-bar D, lever E, and knife F, all constructed as described, and operating substantially as and for the purposes herein set forth.

In testimony that I claim the foregoing, I have hereunto set my hand, this 28th day of August, 1868.

J. J. ANDREW.
